[57] CLAIM

The ornamental design for a manual fuel valve, as shown and described.

DESCRIPTION

FIG. 1 is a perspective view of a manual fuel valve in accordance with the invention;

FIG. 2 is a front view in elevation of the manual fuel valve of FIG. 1;

FIG. 3 is a back view in elevation of the manual fuel valve of FIG. 2;

FIG. 4 is one side view in elevation of the manual fuel valve of FIG. 2;

FIG. 5 is another side view in elevation of the manual fuel valve of FIG. 2 and opposite to that of that of FIG. 4;

FIG. 6 is a bottom view of the manual fuel valve of FIG. 2;

FIG. 7 is a top view of the manual fuel valve of FIG. 2;

FIG. 8 is a perspective view of another embodiment of the manual fuel valve of FIG. 1 without the hexagonal mounting nut shown therein;

FIG. 9 is a front view in elevation of the manual fuel valve of FIG. 8;

FIG. 10 is one side view in elevation of the manual fuel valve of FIG. 9 with the other opposite side view in elevation being the same as in FIG. 5 without the hexagonal nut shown therein; and,

FIG. 11 is a top view of the manual fuel valve of FIG. 9 with the bottom view being the same as shown in FIG. 6.
